UNITED STATES PATENT OFFICE.

HELENE HOEHN, OF WILLIAMSVILLE, NEW YORK.

GARMENT.

1,233,057.

Specification of Letters Patent. Patented July 10, 1917.

Application filed December 22, 1916. Serial No. 138,443.

To all whom it may concern:

Be it known that I, HELENE HOEHN, a citizen of the United States, residing at Williamsville, in the county of Erie and State of New York, have invented new and useful Improvements in Garments, of which the following is a specification.

The present invention relates to wearing apparel and is particularly directed to 10 women's outer garments.

In carrying out the invention it is my object to produce an outer garment for women such as a dress which will conform itself to the figure of the wearer so that stock garments of a determined length may be sold to various purchasers having different bust, 15 hip and waist measurements and wherein the said garment may, without alterations, be arranged to properly fit the various 20 models.

It is a further object of the invention to produce a one-piece dress wherein the back thereof is provided with spaced plaits extending from the shoulder to below the hip 25 lines, producing a panel between the plaits and to provide a belt member comprising two independent sections which cross themselves upon the inner side and at the center of the panel, the ends of the said members 30 being connected to or adjacent to the respective plaits, means being also provided for connecting the ends of the belt members, and the material of the dress being adapted to be gathered or tucked beneath the plaits, 35 whereby the dress may, in this manner, be readily brought to fit differently proportioned women.

It is a still further object of the invention to produce a wearing apparel for women 40 that is self-adjustable or self-fitting with regard to the hip, bust and waistline measurements, which shall be artistic in appearance, comparatively cheap to manufacture and which shall be of an extremely simple construction.

With the above and other objects in view the improvement resides in the construction, combination and arrangement of parts set forth in the following specification and falling within the scope of the appended claims.

In the drawings:

Figure 1 is a view illustrating the improvement and looking toward the front thereof,

Fig. 2 is a similar view but illustrating 55 the dress adjusted to a stout figure,

Fig. 3 is a rear elevation of Fig. 1,

Fig. 4 is a rear elevation of Fig. 2, one of the sections of the belt being unfastened,

Fig. 5 is a sectional view approximately 60 on the line 5—5 of Fig. 1,

Fig. 6 is an enlarged elevation of a fragment of the inner portion of the dress at the belt line thereof,

Fig. 7 is a sectional perspective view illustrating 65 the manner in which the ends of the belt sections are connected and the manner in which the same are closed, and

Fig. 8 is a detail elevation of the strap.

As illustrated by the drawings, the garment 70 1 is of the one-piece type and is provided with an open front.

The back of the garment from points adjacent to the sleeve thereof, to points below the hip line is plaited, as at 2, the folds 75 provided by the plaits being stitched, as illustrated in the drawings, so that the back of the garment, between the said plaits is provided with a panel 3.

The panel 3, at the waistline of the garment is preferably provided with a strap 4 which adds to the ornamentalism of the garment, and the dress, at the folds 1' thereof, inward of the panel 3 is provided with spaced openings 5—5, the said openings being concealed by the plaits 2, even when the said folds 1' of the dress are brought a considerable distance away from each other, as when the dress is worn by stout figures. The said strap is provided with openings 5, 80 85 90 the said openings being concealed by the overlapping plaits 2.

Passing through the openings 5 are the bifurcated ends 6—6 of belt sections 7 and 8, the said bifurcated ends being secured to 95 the back of the dress, as clearly illustrated in Figs. 5 and 7 of the drawings.

The belt members pass through the referred to openings and each of the said belt members or sections at its outer or free 100 end is provided with a button-hole 9.

The numeral 10 designates a strap or connecting member for the ends of the belt sections, the same preferably having its outer face adjacent its ends provided with 105 loops 11 through which the ends of the belt members pass and the said outer face is further provided with a plurality of spaced

securing elements such as buttons which are adapted to be received in the button holes in the ends of the belt members.

The device is adapted to be constructed 5 without elastic, and it will be noted that when the same is arranged upon the person of the wearer the material adjacent to the plaits may be folded and tucked beneath the plaits so that the dress can accommodate 10 itself to a comparatively slight figure, while, of course, less folds are necessary for larger figures. In any event all of the folds are wholly concealed, and from the above description when taken in connection with 15 the drawings, it will be noted that the dress may be arranged to conform to the bust, hip and waist measurements of various figures.

While the improvement has been illustrated and described as an outer garment for 20 women, it is to be understood that the same is not to be thus restricted in its useful application as the same may be employed with equal efficiency upon underwear, undergarments, petticoats, shirts, waists, coats, 25 caps, bonnets, etc.

Having thus described the invention, what I claim is:

1. An outer garment for women having a plaited back providing a panel between 30 the plaits, and adjustable means secured to the back of the dress to the opposite sides

of the plaits and crossing each other and arranged around the waist of the garment, as and for the purpose set forth.

2. A garment for women comprising an 35 open front and having a panel at the back thereof extending from the shoulder to below the hip line of the garment, belt members at the waistline of the garment passing through openings in the back of the dress 40 to the opposite sides of the panel and connected to said dress, and adjustable securing means for the belt members.

3. A dress for women having an open front and having its back provided with a 45 pair of spaced plaits providing between the same a panel which extends from the shoulder to the hip line of the dress, the dress at the folds thereof to the rear of the plaited portions having openings at the waistline 50 thereof, a belt member passing through each of the openings and having an inner bifurcated end, the said bifurcated ends of the belt members straddling each other and being secured to the back of the dress to the 55 rear of the plaits, and means for connecting the ends of the belt members whereby to permit of portions of the garment being tucked beneath the plaits, as and for the purpose set forth.

In testimony whereof I affix my signature.
HELENE HOEHN.
